United States Patent Office

Des. 205,083
Patented June 21, 1966

205,083

LAMP

James F. Fulton, Mamaroneck, N.Y., assignor to Koehler
Manufacturing Company, Marlboro, Mass., a corporation of Massachusetts

Filed May 13, 1965, Ser. No. 85,257

Term of patent 14 years

(Cl. D48—20)

Fig. 1.

Fig. 2.

Fig. 3.

The broken line showing of a lamp bulb is for illustrative purposes only.

I claim:

The ornamental design for a lamp, substantially as shown and described.
